(57) **CLAIM**

The ornamental design for the gas bottle transporter, as shown and described.

DESCRIPTION

FIG. 1 is a front perspective view of the gas bottle transporter of the invention showing the use of the transporter to engage and transport a propane bottle with the bottle being shown in phantom lines to better illustrate the environment of the invention but not forming a part of the invention; FIG. 2 is a front elevational view of the gas bottle transporter of the invention;

FIG. 3 is a left side view of the transporter of FIG. 2, the right side view being a mirror image thereof;

FIG. 4 is a back view of the transporter of FIG. 2;

FIG. 5 is a top end view of the transporter of FIG. 2;

FIG. 6 is a bottom end view of the transporter of the invention; and,

FIG. 7 is a perspective view of the transporter of the invention, showing the handle thereof in the collapsed position.
